FIG.1.

FIG.2.

FIG.3.

MERRILL G. BASSLER,
INVENTOR.

BY *erville R. Seidner*

AGENT.

UNITED STATES PATENT OFFICE

173,254

TONGS

Merrill G. Bassler, El Monte, Calif.

Application February 26, 1954, Serial No. 29,234

Term of patent 14 years

(Cl. D44—4)

To all whom it may concern:

Be it known that I, Merrill G. Bassler, a citizen of the United States, residing at El Monte, in the county of Los Angeles and State of California, have invented a new, original, and ornamental Design for Tongs, of which the following is a specification, reference being had to the accompanying drawing, forming part thereof, and wherein,

Fig. 1 is a perspective view of a pair of tongs showing my new design;

Fig. 2 is an end elevation view thereof; and

Fig. 3 is a side elevation view thereof.

I claim:

The ornamental design for tongs, as shown.
